UNITED STATES PATENT OFFICE.

WILLIAM V. MOAK, OF ALBANY, NEW YORK.

ELECTRIC RAILWAY-SIGNAL.

SPECIFICATION forming part of Letters Patent No. 750,296, dated January 26, 1904.

Application filed December 8, 1902. Serial No. 134,289. (No model.)

To all whom it may concern:

Be it known that I, WILLIAM V. MOAK, a citizen of the United States of America, and a resident of the city and county of Albany and State of New York, have invented certain new and useful Improvements in Electric Railway-Signals, of which the following is a specification.

My invention relates to electric railway-signals operated by relays; and the objects of my invention are to construct a railway-signal which will be operated automatically by trains entering and leaving the block which the signal is to clear and which shall be simple and economical of construction, positive of action, unaffected by variations of weather or temperature, and may be operated at a considerable distance from the signal. I attain these objects by means of the mechanism illustrated in the accompanying drawings, in which—

Figure 1 is a front view of the operating mechanism of my signal with the cover removed, together with a plan view of the railway-tracks and relays for operating the signal. Fig. 2 is a vertical section of the operating mechanism at X X, Fig. 1. Fig. 3 is an enlarged view of the compound trip-lever. Fig. 4 is a side view of the circuit-breaker. Fig. 5 is a plan view of the circuit-breaker. Similar characters refer to similar parts throughout the several views.

A is the signal-blade, which is displayed in the usual position elevated on a pole by the side of a railway-track. The signal-blade A is mounted upon the shaft B and is attached to and turns with the said shaft.

Attached to the blade A or formed by an extension thereof is the overbalance C, extending on the opposite side of the shaft B and of sufficient weight that when left free to act it will raise and hold the blade A in a horizontal position, as shown in Fig. 1, which is the normal position for the blade. The projection or knob N, Fig. 1, acts as a stop to prevent the overbalance C from descending so far as to raise the blade above the horizontal position, and the projection M, Fig. 2, acts as a stop to prevent the blade A dropping or descending too far in the other direction when

acted upon by the wheel D, as hereinafter described.

D is a wheel mounted loosely on the shaft B and provided with cogs K in its periphery, which mesh with the cogs K' of the wheel J'. The wheel D is also provided with projections or catches d d d, arranged upon one side of said wheel at regular intervals.

E E' is a compound lever acted upon at each movement or trip of the wheel D and called a "compound trip-lever." It is composed of two parts E and E', joined together by the pivot e, the part E turning upon the pivot e' and the part E' being provided with the elongated slot e² and adapted to slide along and turn upon the pivot e³, so that the whole lever may take the position indicated by the dotted lines, Figs. 1 and 3.

F is an armature composed of soft magnetic iron and is attached to the lower end of part E of the compound trip-lever and arranged so that when the said lever is straight, as shown in Fig. 1, the armature F will rest in contact with the electromagnet S.

G and G' are two motors mounted on opposite ends of the shaft H in such positions that both motors cannot at the same time stop on a dead-center, so that when the electric current is turned on one or the other motor is sure to start. Upon the shaft H between the two motors is the worm screw-thread I, which meshes with the worm-teeth on the periphery of the wheel J, which is mounted stationary on the shaft L and adapted to turn said shaft. J' is a wheel of smaller diameter also mounted stationary on said shaft L and is turned by said shaft, or it may be attached to or a part of said wheel J, revolving with it, but with a periphery of less diameter, for the purpose of transmitting more power. The periphery of the wheel J' is provided with cogs K', adapted to mesh with the cogs K on the wheel D.

P is a circuit-breaking spring attached to the inside of the covering or box inclosing the wheel D and the other operating mechanism. The circuit-breaking spring P may be of any desired construction, as the two spring-wires p p, arranged to be operated by the circuit-breaking arm R. The circuit-breaking arm

R is fixedly attached to the shaft B and in such position and so arranged that when the shaft B revolves it carries the circuit-breaking arm R around until its end r, composed of non-conducting material, comes between the wire springs p p and separates them, thus breaking the circuit.

T is a block or support, of any desired form or material, fixedly attached to the shaft B and revolving with said shaft and to which the compound trip-lever E E' is attached by the bolts or pins e' and e'', acting as the stationary pivots of the respective component parts of said lever, the said lever being carried by said block T as the same revolves with the shaft B. Said block T also supports and carries the magnet S.

W is a railway-track divided into blocks of any desired length.

O is a track-relay battery, and Q is a second track-relay battery, situated in the first block. A section of one of the rails of the railway-track opposite each battery is insulated. The track-relays may be constructed in the usual manner and are designated in the accompanying drawings as 1 and 2. No. 3 is the signal-relay.

The action of the system of relays in connection with the signal is as follows: Relay No. 1, the armature of which has two separate contacts, is connected to the first section of the insulated rail and is kept normally closed by the current of battery O, which is connected to the same section of the insulated rail, as shown by the drawings. When a train touches that insulated section of the rail to which relay 1 and battery O are connected, as shown by the drawings, battery O is short-circuited through the axles of the car-wheels, thus depriving relay 1 of the current of battery O, thereby permitting armature 8 of relay No. 1 to be withdrawn by means of a spring or force of gravity from the magnets and coming in contact with the connection-points, (designated as 6 and 7,) thus making a double connection, as shown in the drawings. This double connection having been made by relay 1, a circuit from battery 5 is completed, running through armature 12 in relay 2, through lever-magnet S in the signal, and through signal-relay 3, magnetizing lever-magnet S in the signal for the purpose heretofore described and magnetizing the magnets of signal-relay 3 for the purpose hereinafter described. The magnets of relay 3 becoming thus magnetized, armature 10 of relay 3 is drawn toward the magnets coming in contact with contact-point 9, as shown in the drawings, thus permitting the circuit of battery 4 to be completed by armature 8, relay 1 touching contact-point 6, which it does when battery O is short-circuited. This circuit of battery 4, running through armature 8 in relay 1 and armature 10 in relay 3, operates the motors G and G'.

When the train leaves the

first section of the insulated track, in which is located relay 1 and battery O, the circuit of battery O is again completed through relay 1, armature 8 being drawn away from contact-points 6 and 7, thereby breaking the circuit of battery 5. Relay 2 is a triple-pointed relay, as shown in the drawings, and performs the same function for the succeeding signal that relay 1 does for the first or immediate signal. When the train strikes the second section of the insulated rail, in which is located battery Q and relay 2, battery Q is short-circuited through the axles of the wheels, thereby demagnetizing relay-magnet 2 and permitting the armature 12 to be withdrawn by spring or force of gravity from the magnets and contact-point 11, thereby breaking circuit of battery 5, demagnetizing lever-magnet S, and permitting the signal to resume its normal position, as heretofore described, and making it impossible for any circuit to be made through relay 2 so long as the train remains in the second section of the insulated track, thereby showing to an approaching train that the track is not clear, as indicated by the wing of the signal failing to dip when the approaching train strikes the first section of the insulated track.

The operation of my invention is as follows: When the train enters the block at the point from which the signal is to clear opposite the battery O, if the track is clear for the space which signal is to protect an electrical connection is made, the current passing to the magnet S. The same is set and the armature F held firmly against it. At the same time the current starts the motors G and G'. These motors turn the shaft H and the worm I, which turns the wheel J, which turns the shaft L, which turns the wheel J', which turns the wheel D. As the wheel D revolves one of the projections or catches d comes in contact with the compound trip-lever near the upper end of E'. The lever being held rigid by the armature F being held firmly against the magnet S, the wheel D carries the lever in its straight position, together with the block T and shaft B, around until the signal-blade A strikes the stop M, Fig. 2, and is in the position shown by the dotted lines in Fig. 1, indicating safety for the train to proceed. By the time the signal-blade has reached this position the circuit-breaking arm R has reached the spring circuit-breaker P and broken the circuit, so as to cut off the current from the motors G G'. The magnet S remains set and holds the compound lever rigid until the train passes the second relay-battery Q, where it cuts off the current from the magnet S, and the magnet S thereupon releases the armature F, and the overbalance C pressing the end of lever against the catch d the two parts of the lever will turn upon the pivots e, e', and e'', and the lever will take the position shown by the dotted lines, Figs. 1 and 3, so that the end of

the lever will slip under the catch *d* and the signal-blade will assume its horizontal position, the same operation being repeated upon the approach of each train, the following catch *d* acting upon the lever at each succeeding operation. If the train has not passed the second relay-battery *Q* and relay *V*, the device will not operate, showing that the track is not clear.

10 Constructed in this way the signal may be operated from any desired distance, the action will always be positive, the operating mechanism may be readily housed in and protected with suitable covering and not affected by changes in the weather or temperature, and the whole apparatus constructed and maintained with the least expense and greatest efficiency.

What I claim as my invention, and desire to 20 secure by Letters Patent, is—

1. In an electric railway-signal operated automatically by means of track-relays; a compound lever mounted fixedly on the semaphore-shaft; said compound lever being composed of two parts pivoted together at their adjacent ends, each part turning on its separate stationary pivot; a driving-wheel loosely mounted on said semaphore-shaft and adapted to engage said lever; an electromagnet also 25 fixedly mounted upon said semaphore-shaft controlling said lever, in combination with an electric motor operating said driving-wheel and electrical circuits controlling said motor and said magnet by means of said track-relays, substantially as described and for the purposes set forth.

2. In an electric signal for railways, a signal-blade mounted fixedly upon the semaphore-shaft; a driving-wheel mounted loosely upon said shaft; a compound lever, composed of two parts pivoted together at their adjacent ends and each part turning on its separate pivot, mounted fixedly upon said shaft; an electromagnet also mounted fixedly upon said shaft; said electromagnet adapted to control said compound lever and when magnetized to hold said compound lever rigid; projections on said driving-wheel adapted to engage said compound lever when the same is held rigid 45 by the electromagnet and not otherwise; one or more electric motors mounted upon another shaft and adjusted not to stop on a dead-center; means for operating said driving-wheel by said motors; electrical circuits connecting said motors and said magnet with the track-relays, whereby said motors and said magnet will be controlled by said track-relays and operated automatically by passing trains, substantially as described and for the purposes 50 set forth.

3. An electrical railway-signal consisting of a signal-blade mounted fixedly upon a shaft; a driving-wheel provided with catches and mounted loosely upon the same shaft; a compound lever mounted fixedly upon the same

shaft and adapted to be engaged by said catches, when the compound lever is rigid and straight; an armature of soft iron attached to one end of said compound lever and adapted to come in contact with an electromagnet; an electromagnet controlling said compound lever and holding it rigid and straight when magnetized and releasing it when demagnetized; an electrical circuit through said electromagnet and a signal-relay said circuit being 70 controlled by the track-relays; a motor mounted upon another shaft; an electrical circuit through said motor controlled by a track-relay; intermediate connections for operating said driving-wheel by said motor; a signal-relay; two or more track-relays arranged and adapted to be operated by the passing train, substantially as described and for the purposes 75 set forth.

4. In an electrical railway-signal, adapted 80 to be operated automatically by means of passing trains; a signal-blade mounted fixedly upon a shaft; an overbalance on the opposite side of said shaft adapted to hold said signal-blade in a horizontal position when the mechanism of 85 said signal is not acted upon by an electrical current; a driving-wheel mounted loosely upon said shaft; one or more catches upon said wheel adapted to engage a compound lever mounted fixedly upon said shaft and thereby 90 to revolve said shaft, moving said signal-blade from its horizontal position; an electromagnet revolving with said shaft and adapted to hold said shaft in position when magnetized and to release the same when demagnetized; an electrical circuit controlled by a track-relay 95 through said electromagnet; a circuit-breaking arm fixedly mounted upon said shaft and arranged and adapted to come in contact with a circuit-breaking spring when said shaft revolves; a circuit-breaking spring adapted to be acted upon by said current-breaking arm, and when so acted upon to break the motor-circuit; one or more motors mounted upon another shaft; means for operating said driving-wheel by means of one or more intermediate gear wheels and shafts, in combination with two track-relays and one signal-relay and an electrical circuit controlled by a track-relay 105 through the armature connection in the signal-relay to said motors, which track-relays are operated automatically by means of passing trains, substantially as described and for the purposes set forth.

5. In an electric railway-signal, two insulated sections of the rail; an electric battery connected to each of said insulated sections; two track-relays one connected to each of said sections and operated by the current of said batteries automatically by means of passing 110 trains; an electric railway-signal and means for operating the same by an electric motor; an electric motor adapted to operate the same; an electromagnet controlling said signal; a signal-relay and an electric battery connected 115 120 to said motor; an electrical circuit controlled by a track-relay through the armature connection in the signal-relay to said motor, which track-relays are operated automatically by means of passing trains, substantially as described and for the purposes set forth.

with said signal - relay; an electric circuit through said signal-relay and the said electromagnet and controlled by said track-relays; substantially as described and for the uses and purposes heretofore set forth.

6. In a system of electric railway-signals, a railway divided into signal-blocks; two insulated sections of the rail in each signal-block; an electric battery connected to each section 10 of insulated rail; two track-relays one connected to each of said insulated sections of each block and operated by the current of said batteries automatically by means of passing trains; the second section of each individual 15 signal-block being the first section of the following or succeeding block; the second-section track-relay of each individual signal-block being the first-section track-relay in the following or succeeding block; an electric railway-signal located in each block; an electro-

magnet controlling the action of the signal-blade of each signal, electrical connection from the second-section track-relay of the immediate semaphore to the following or succeeding semaphore; a signal-relay and a battery connected therewith for each semaphore; the circuit of said battery being controlled by a track-relay and completed through the signal-relay and the electromagnet which it operates, said signal-relay with said track-relay controlling the motor-circuit, substantially as described and for the uses and purposes heretofore set forth.

Signed by me at Albany, New York, this 29th day of November, 1902.

WILLIAM V. MOAK.
